UNITED STATES PATENT OFFICE

172,325

COMBINED PICTURE FRAME AND PLANTER BOX

Julius Adler, Chicago, Ill.

Application March 9, 1954, Serial No. 29,446

Term of patent 7 years

(Cl. D29—20)

To all whom it may concern:

Be it known that I, Julius Adler, residing at 5574 West Congress, in the city of Chicago, county of Cook, and State of Illinois, have invented a new, original, and ornamental Design for a Combined Picture Frame and Planter Box, of which the following is a specification, reference being had to the accompanying drawing, forming a part hereof.

Fig. 1 is a front elevational view of a combined picture frame and planter box embodying my new design;

Fig. 2 is a side elevational view thereof; and

Fig. 3 is a sectional view thereof taken along the line 3—3 of Fig. 1 and drawn on an enlarged scale with the central portion broken away for convenience of illustration only.

I claim:

The ornamental design for a combined picture frame and planter box, as shown.
